DESIGN FOR A JEWELRY FINDING

John E. Sutherlin, New Orleans, La.

Original design application December 18, 1945,
Serial No. 124,830. Divided and this applica-
tion January 8, 1946, Serial No. 125,364

Term of patent 14 years

(Cl. D45—1)

To all whom it may concern:

Be it known that I, John E. Sutherlin, a citizen of the United States, residing at New Orleans, in the Parish of Orleans and State of Louisiana, have invented a new, original, and ornamental Design for a Jewelry Finding, of which the following is a specification, reference being had to the accompanying drawing, forming a part thereof, wherein:

Fig. 1 is a front elevational view of a jewelry finding showing my new design;

Fig. 2 is a rear elevational view thereof;
Fig. 3 is a side elevational view of the jewelry finding.

This application is a division of application Ser. No. D-124,830, filed December 18, 1945.

I claim:

The ornamental design for a jewelry finding, substantially as shown.

JOHN E. SUTHERLIN.
